UNITED STATES PATENT OFFICE.

LEO BROWN, OF KANSAS CITY, MISSOURI, ASSIGNOR TO LINCOLN STORES, INC., OF ST. LOUIS, MISSOURI, A CORPORATION OF MISSOURI.

DESIGN FOR A STORE FRONT.

Application filed June 21, 1928. Serial No. 27,215. Term of patent 14 years.

To all whom it may concern:

Be it known that I, LEO BROWN, a citizen of the United States, residing in the city of Kansas City, county of Jackson, State of Missouri, have invented a certain new, original, and ornamental Design for a Store Front, of which the following is a specification, reference being made to the accompanying drawing, forming a part thereof, and in which

Figure 1 illustrates in elevation a store-front embodying my design, Figure 2 being an approximate sectional view of the store-front taken along the line 2—2, Figure 1.

I claim:

The ornamental design for a store-front, substantially as shown.

LEO BROWN.
